UNITED STATES PATENT OFFICE.

HENRY K. DAY, OF ELYRIA, OHIO.

HOUSE-DOOR LETTER-BOX.

SPECIFICATION forming part of Letters Patent No. 460,117, dated September 29, 1891.

Application filed December 18, 1890. Serial No. 375,061. (Model.)

To all whom it may concern:

Be it known that I, HENRY K. DAY, of Elyria, in the county of Lorain and State of Ohio, have invented a new and useful Improvement 5 in Letter-Boxes, of which the following is a full, clear, and exact description.

My invention relates to an improvement in letter-boxes, and has for its object to provide a box of simple and durable construction 10 capable of being conveniently and expeditiously opened by the postman and of being locked after the mail has been placed therein.

A further object of the invention is to provide a box the front of which may be utilized 15 for the attachment of a name-plate, if desired, and also to attach to the box a paper or package receptacle, quickly placed in position for use, but which when not required may be practically hidden.

20 The invention consists in the novel construction and combination of the several parts, as will be hereinafter fully set forth, and pointed out in the claims.

Reference is to be had to the accompanying 25 drawings, forming a part of this specification, in which similar figures and letters of reference indicate corresponding parts in all the views.

Figure 1 is a rear elevation of a letter-box, 30 the package-receptacle being folded up thereon. Fig. 2 is a vertical section taken near the center, the package-receptacle being illustrated in position for use; and Fig. 3 is an end view of the letter-box with the package-receptacle in the position illustrated in Fig. 1.

The body of the box consists of a skeleton 35 frame A and a drop door B. The frame is preferably of rectangular shape, open at the front and back and adapted for attachment 40 to a door or other support through the medium of cleats or brackets 10 or their equivalents. The drop-door is preferably wider and longer than the frame and is pivoted in the lower portion of the latter, usually by passing 45 a pin 11 through the upturned ends of the angle-plate 11^a, secured to the inner face of the door, the horizontal member whereof is preferably of the width of the bottom of the frame and extends over said bottom, being 50 provided with arms 12, extending upward from the inner edge. The letters when placed

in the box are deposited between the arm 12 and the door. The door is usually provided with a series of apertures at one side, and a gong 14 is secured upon the outer face, covering the apertures. The hammer 15 of the gong is fast to one end of a spring 16. The spring is usually made to comprise two members, as shown in dotted lines, Fig. 1, and is bent somewhat to a U shape. A coil is formed 60 at the bow portion of the spring and loosely placed around a suitable stud. One member is essentially straight, and at the lower end of it a hammer is placed. The other member is curved inward at or near the center, forming 65 an angular projection 17, and the bottom of the member is bent to produce an angular foot, the inner end whereof is secured to the door. Latch-levers 18 are somewhat centrally pivoted upon the inner face of the door near 70 the top. Two levers are usually employed, the inner extremities of which overlap and are pivotally connected by a single stud 19 with a vertically-movable trip-bar 20, located at the center of the door, which trip-bar is of sufficient length to extend above the frame when the door is closed and terminates at its upper end in a knob or a hook 21. Latch-heads a are formed at the outer extremities of the levers and extend inward at 80 a right angle to the door, being slotted to receive studs 22, which serve as keepers and are located upon the inner face of the sides of the frame. The trip-bar is provided with a slot through which a pin passes, as shown in 85 Fig. 1. The slot limits the movement of the bar, and the heads of the latch-levers are held normally in position to engage with their keepers by means of a spring 23, having one end attached to the door and the other bearing against the under side of the stud 19. In order to disengage the latch-levers from the frame, the trip-bar is pushed downward; but as soon as released the bar is forced upward by the spring and the levers are restored to 90 their normal position. At both the upward and downward movement of the trip-bar the gong is sounded, and this is accomplished through the medium of a pin 24, extending outward from the trip-bar through a suitable slot in the door, engaging with the angular projection 17 of the spring carrying the 95 100

hammer, whereby the hammer member of the spring is vibrated each time the pin passes the projection and an alarm is sounded.

In connection with the trip-bar a locking device is employed, which consists of a three-armed bolt 25, pivoted upon the door near the lower edge thereof. The bolt is composed of three members, comprising two horizontal members and one vertical member. The vertical member is adapted to engage with the lower end of the trip-bar, which is slightly beveled, and a spring 26 is attached to one horizontal member of the bolt, the other end of the spring being secured to the door. The third member of the bolt is adapted to rest upon a locking-bar 27, placed horizontally upon the door, the outer end only of the bar being secured to the door, the inner end, with which the bolt engages, being free to move inward or outward. The locking-bar is made of spring metal, and when in its normal position the bolt-arm rests upon the upper edge of it, as shown in Fig. 1. The free end of the locking-bar, however, may be pushed inward through the medium of a button 28, located at the front of the door and passing through an aperture therein to a connection with the bar, and when the free end of the bar is thus pressed inward the spring 26 acts to force the horizontal member engaging with the locking-bar downward between the bar and the door, thus causing the vertical member of the bolt to engage with the beveled end of the trip-bar, and when the bolt 25 is in such engagement with the trip-bar the said bar cannot be pressed downward to release the door from the frame until a key has been inserted in a key-hole beneath the latch 25 and the member thereof engaging with the locking-bar forced upward.

In connection with the box I employ a package-receptacle C, which usually consists of a horizontal bar 29, provided with a central handle 30 and essentially U or V shaped arms 31, extending upward from the ends of the bar, the outer members being, preferably, shorter than the inner ones. The bar-section of the receptacle is located below the box, and when not in use practically engages with its bottom surface. The longer member of the arm extends upward through apertures in brackets 32, secured to the outer side faces of the frame near the bottom, and the shorter member bears against the inner face of the cover near the side margins thereof, as shown in Fig. 1. Both members of the arms have their upper ends enlarged in any suitable or approved manner.

The gong and its striking mechanism are concealed and protected from injury by a plate 33, semicircular in cross-section or dome-shaped, screwed, bolted, or otherwise attached to the cover. This plate usually has the word "Letters" produced upon it; but, if found desirable, the said word may be concealed by a name-plate 34, connected with the dome-shaped plate only.

When the member of the three-armed bolt 25 rests upon the locking-bar 27, as shown in Fig. 1, the trip-bar 20 is released from the bolt 70 and may be pressed down by the carrier to disengage the latch-levers 18 from the studs 22 on the frame, when the door will drop by gravity, and the letters may be placed in the box. After the letters have been deposited 75 in the box the lid is raised, when the catch-levers 18 will engage the studs 22 and hold the door closed. Now to lock the door it is only necessary to push the locking-bar 27 inward by its knob 28 to disengage the member 80 of the bolt 25 from the said bar, when the vertical member of the said bolt will be thrown under the lower end of the trip-bar 20, and thereby prevent any downward movement of the said bar and consequently prevent the 85 latch-levers 18 from being disengaged from the studs 22 of the frame. To unlock the door, a key is inserted in the key-hole below the bolt 25 and the said bolt turned upon its pivot to throw its vertical member from below the trip-bar 20, when the bolt will be supported in this position by the locking-bar 27 and the door readily opened by manipulating the trip-bar, as before described. In the event that packages are to be delivered, the rack-like receptacle C is drawn downward, whereupon the shorter members of the arms spring 90 outward from the longer members and form a pocket.

It will be understood from the description 100 heretofore given that upon both the upward and the downward movement of the trip-bar an alarm is sounded upon the gong.

Having thus described my invention, I claim as new and desire to secure by Letters Patent—

1. In a letter-box, the combination, with a frame and a door hinged thereto, of latch-levers and a sliding trip-bar pivotally connected with the levers, as and for the purpose specified.

2. In a letter-box, the combination, with a frame and a door hinged thereto, latch-levers locking the door to the frame, and a sliding trip-bar pivotally connected with the latch-levers, of a spring-pressed angular bolt pivoted below the trip-bar and a spring locking-bar secured at one end and free at the other, one member of the angular bolt being adapted to engage with the locking-bar and the other with the trip-bar, substantially as and for the purpose specified.

3. In a letter-box, the combination, with a frame provided with keepers and a drop-door hinged to the frame, of a trip-bar held to slide 125 upon the door, latch-levers fulcrumed at each side of the trip-bar and having their inner ends pivoted to said bar, and a spring having a bearing against the trip-bar at its pivotal connection with the latch-levers, as and for 130 the purpose specified.

4. In a letter-box, the combination, with the frame and a drop-door hinged thereto, of a trip-bar held to slide upon the door, latch-

levers fulcrumed at each side of the trip-bar 5
engaging with the frame and having their inner
ends pivotally connected to the trip-bar,
a spring bearing against the trip-bar at its
connection with the levers, a gong located
upon the outer face of the door, a spring car-
rying a hammer adapted for engagement with
the gong, and a pin connected with the trip-
bar and engaging the said spring, as and for
the purpose specified.

5. In a letter-box, the combination, with a
frame, a drop-door hinged thereto and pro-
vided with a horizontal extension at its piv-
otal end, and arms projected upward from
15 said extension, of a spring-pressed trip-bar
held to slide upon the cover, latch-levers ful-
crumed at each side of the trip-bar and hav-
ing their inner ends connected therewith, a
spring-pressed angled bolt fulcrumed upon
20 the door below the trip-bar and provided with
a vertical and a horizontal member, the vertical
member being adapted for engagement with
the trip-bar, a spring locking-bar se-
cured at one end and free at the other end,
25 the free end being adapted for engagement
with the horizontal member of the bolt, and
a knob located upon the outer face of the
door and connected with the free end of the
locking-bar, as and for the purpose specified.

30 6. In a letter-box, the combination, with a
box, of a package receptacle or pocket con-

sisting of a bar located beneath the box and
essentially U-shaped arms extending upward
from the ends of the bar, one member of said
arms being adapted to slide in bearings at-
35 tached to the box, as and for the purpose set
forth.

7. In a letter-box, the combination, with a
box provided with apertured brackets at-
tached to its ends, of a package receptacle or
40 pocket consisting of a bar located beneath
the box and having an attached handle and
essentially U-shaped arms projected upward
from the ends of the bar, the outer members
45 of the said arms being shorter than the inner
members, and the inner members being held
to slide in the brackets of the box, as and for
the purpose set forth.

8. In a letter-box, the combination, with
the door thereof having a gong attached to its
outer face, and striking mechanism located
partially within and partially without the
door, of a casing-plate, semicircular in cross-
50 section, secured to the outer face of the door
and covering the gong and the striking mech-
anism thereof, the said casing-plate being
adapted to receive a name-plate, as and for
the purpose specified.
